OTHER PUBLICATIONS

Office Action with regard to the counterpart U.S. Appl. No. 29/596,638 dated Feb. 5, 2020.

FIG. 1 is a perspective view taken from a top, left side of an electronic device for providing travel information according to a first embodiment of our design;

FIG. 2 is a top plan view of the electronic device for providing travel information of FIG. 1;
FIG. 3 is a bottom plan view of the electronic device for providing travel information of FIG. 1;
FIG. 4 is a right side elevation view of the electronic device for providing travel information of FIG. 1;
FIG. 5 is a left side elevation view of the electronic device for providing travel information of FIG. 1;
FIG. 6 is a front elevation view of the electronic device for providing travel information of FIG. 1;
FIG. 7 is a rear elevation view of the electronic device for providing travel information of FIG. 1;
FIG. 8 is a perspective view taken from a top, left side of an electronic device for providing travel information according to a second embodiment of our design;
FIG. 9 is a top plan view of the electronic device for providing travel information of FIG. 8;
FIG. 10 is a bottom plan view of the electronic device for providing travel information of FIG. 8;
FIG. 11 is a right side elevation view of the electronic device for providing travel information of FIG. 8;
FIG. 12 is a left side elevation view of the electronic device for providing travel information of FIG. 8;
FIG. 13 is a front elevation view of the electronic device for providing travel information of FIG. 8; and,
FIG. 14 is a rear elevation view of the electronic device for providing travel information of FIG. 8.
Throughout the Figures, where shown, (i) the broken lines showing additional structure of the electronic device for providing travel information are for illustrative purposes only and form no part of the claimed design; and (ii) the unshaded surfaces form no part of the claimed design.
